UNITED STATES PATENT OFFICE.

JACOB A. HENRY, OF PEABODY, KANSAS.

FARM-GATE.

SPECIFICATION forming part of Letters Patent No. 228,896, dated June 15, 1880.

Application filed February 12, 1880.

To all whom it may concern:

Be it known that I, JACOB A. HENRY, of Peabody, in the county of Marion and State of Kansas, have invented certain new and 5 useful Improvements in Gates; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

It is well known that over many sections of territory, especially over the portions which 15 have large areas substantially level, the wind blows with great force, and often for long times, resulting in the destruction of property and structures of various sorts, doing especially great damage to gates and fences.

20 The object of this invention is to provide a simple, cheap, and easily-constructed support for gates, to be used on farms where gates are liable to the damages above mentioned.

It consists, first, in a novel and simple arrangement for supporting the gate, my device being intended to take the place of ordinary posts embedded in the ground.

It consists, secondly, in constructing a post-frame of cast metal in such manner that the 30 parts of the frame can be easily packed in convenient shape for transportation.

Figure 1 is a perspective view of the post-frame embodying my improvements. Fig. 2 is a perspective showing a slightly-modified construction. Fig. 3 is a vertical section of the latching or fastening devices; and Fig. 4, is a vertical section, showing the front and bottom of the post-frame when folded together for transportation.

40 In the drawings, the gate is shown as having two swinging parts, A A', although this duplication of the swinging parts of the gate is not essential to my invention, it being as applicable to gates in which there is but one hinged and swinging portion. The gate A is hinged in any desired manner to a frame, (about to be described,) in lieu of the ordinary gate-posts employed for this purpose. This frame is represented in the drawings as being constructed 45 of an inner end piece, B, bottom B', and lateral walls B²B². The top and outer end of the frame are preferably left open, as shown.

C C represent sills attached to and arranged below the frame-work, whereby the frame is provided with additional lateral support 55 against its being upset or overturned.

c c are braces secured, respectively, at one end to the sills C C and at the other ends to the side walls, B, of the frame-work of the gate-support.

The post-frame may be constructed of wood, as represented in Fig. 2, if desired; but the construction which I preferably manufacture and employ is that shown in Fig. 1, in which construction the frame is composed of four 65 castings so shaped relative to each other that they can be packed in very small space for shipment or transportation. The hinged post B and the bottom B' are arranged to be hinged together, as shown at b, so that the posts can 70 be folded down upon the bottom, as shown in Fig. 4. The part B is cast with flanges or cleats b' and the bottom part with similar flanges or cleats b², whereby the side pieces, B² B², of the frame can be secured to the other parts by 75 small bolts or rivets at b³. The flanges or cleats b² on the bottom B' are arranged to be outside of the wall B², and the flanges or cleats b' on the upright part B are situated on the inside of the wall, so that the flanges B' and B² shall 80 not interfere with each other when the frames are being packed or folded.

The frame, after being constructed in substantially the manner described, is filled with heavy stones, which, as is well known, are found 85 in some localities in great abundance, and are generally conveyed to and deposited along the edges of fields. When thus filled and weighed down with stones I have found that it is ordinarily impossible for the wind to overturn or 90 displace or otherwise damage the gate.

This construction obviates the necessity of digging the deep and expensive post-holes necessary when the ordinary posts are used to support gates.

If desired, stakes may be driven by the side of the frame, or in contact with the sills C C, for the purpose of assisting in preventing displacement.

If at any time it be desired to move the gate, 100 it can be conveniently moved, as will be readily seen, after removing the stones or other weight contained in the casings B B' B².

The gate is fastened by means of the fol-

lowing devices: D represents an eye or cleat provided with an aperture at or near the upper end of one of the swinging parts of the gate when two swinging parts are used, and 5 D' represents a similar eye or perforated cleat at or near the bottom of the same part. E E' represent similar eyes or cleats at or near the upper edge of the other swinging part when two swinging parts are used, and E' E' similar devices at or near the lower edge of the same part. A passage-way is formed inside the outer upright of one of the swinging parts, as shown at F. G is a sliding rod, bent substantially as shown, so as to have a handle or 15 loop part, g, vertical shank g', situated within the passage F, a downwardly-projecting catch, g², at the lower end, and a downwardly-projecting catch, g³, formed by bending down the upper end of the rod below the loop or handle 20 g. f is a slot in the frame of the gate, which permits the lower part of the fastening-rod G to rise and fall to a limited extent.

When it is desired to fasten the gate the eyes or cleats D D' are brought, respectively, 25 in vertical line with the corresponding cleats E E', and the fastening-rod G is then dropped so that the part g² connects together the lower set of eyes and the part g³ connects the upper

set. In this way I am enabled to secure very firmly together the two parts of the gate (or 30 the gate and post and frame) both at the upper edge and at the lower edge, where the greatest strain occurs. Moreover, I am enabled to accomplish this purpose by a single rod, which rises and falls but a very limited 35 distance, it not being necessary to withdraw the rod upward the full length of the gate to open the same, nor to push it down the full length when it is desired to close it.

What I claim is—

1. The herein-described device for holding a gate in place, consisting of the frame-work B B' B², constructed and arranged to be filled and weighed down with stones, and to be readily removed, substantially as set forth. 40

2. In a gate-post frame, the combination of the vertical part B and the bottom part, B', hinged together, substantially as set forth. 45

In testimony that I claim the foregoing I have hereunto set my hand this 27th day of 50 January, 1880.

JACOB ALPHARD HENRY.
